UNITED STATES PATENT OFFICE.

ARTHUR TREVOR DAWSON AND GEORGE THOMAS BUCKHAM, OF LONDON, ENGLAND, ASSIGNORS TO VICKERS SONS & MAXIM, LIMITED, OF LONDON, ENGLAND.

RECOIL APPARATUS FOR GUNS.

SPECIFICATION forming part of Letters Patent No. 718,749, dated January 20, 1903.

Application filed December 9, 1901. Serial No. 85,296. (No model.)

To all whom it may concern:

Be it known that we, ARTHUR TREVOR DAWSON, late lieutenant of Royal Navy, and GEORGE THOMAS BUCKHAM, engineer, both 5 residing at 32 Victoria street, Westminster, in the county of London, England, subjects of the King of Great Britain, have invented certain new and useful Improvements in Recoil Apparatus for Guns, of which the following is a specification.

This invention relates to quick-firing and other gun mountings that are provided with a hydraulic buffer for absorbing the energy of recoil and a recuperator for running the 15 gun forward to firing position after recoil. The chief object of our invention is to provide means for controlling the velocity with which the gun runs forward after recoil, said invention being applicable to that form of recoil-buffer in which the cylinder has a hollow piston-rod and a retarding-ram extending inwardly from one end of the cylinder into the said hollow piston-rod. The piston is partly withdrawn from the ram during the recoil, 20 thereby leaving in the piston-rod a space which becomes filled with liquid that must be displaced by the ram while the gun is being run forward after recoil, provision being made for the displaced liquid to be forced through a 25 restricted passage, thus controlling the velocity with which the gun is returned to its firing position. We provide improved means for controlling the flow of the said liquid to and from the said hollow piston-rod, as will 30 be hereinafter described, the chief feature of our invention being the formation of the hollow piston-rod and the ram so that the liquid in the hollow piston-rod can only escape back to the recoil-cylinder through an opening or 35 passage which gradually diminishes in area during the forward movement of the piston as the gun regains its firing position.

We will now describe our invention with the aid of the accompanying drawings, in 45 which—

Figure 1 is a longitudinal section of a hydraulic buffer or recoil-cylinder provided with our improvements. Figs. 2 and 3 are transverse sections thereof, taken, respectively, on 50 the lines 1 1 and 2 2. Fig. 4 is a longitudinal

section of a recoil-cylinder provided with a modified form of our improvements. Figs. 5 and 6 are transverse sections thereof, taken, respectively, on the lines 3 3 and 4 4.

Referring to the drawings, the reference-letter A is the recoil-cylinder; B, the hollow piston-rod; B', its piston; C, the ram which projects from one end of the cylinder and enters the hollow piston-rod.

A' is the key within the cylinder A, and B² 60 the aperture in said piston that acts in conjunction with said key for increasing the resistance to the recoil as said piston travels in the cylinder during the recoil movement of the gun.

C' is the lug or bracket on the gun, to which the piston-rod is secured.

In Figs. 1, 2, and 3, b b are inclined passages formed through the hollow piston-rod B and serving to connect the annular space existing 70 between the ram C and the hollow piston-rod with the space a in the cylinder A behind the piston. b' is a bush screwed or otherwise affixed in a cavity formed in the front face of said piston. This bush accurately fits the 75 ram C, with the exception of a small longitudinal passage b², formed therein and through which liquid can pass from the annular space around the said ram to the space in front of the piston in the cylinder A. Immediately 80 behind the said bush we provide a sleeve-valve b³, which is capable of sliding in the piston B. By means of a spring b⁴ this valve is normally kept in a position with its forward end tightly pressed against the end b⁵ 85 of the aforesaid bush b', which serves as a valve-seat for it. The said ram has one or more taper grooves or flats c, Fig. 3, whose greatest depth or width is at the rear end of said ram, said grooves or flats gradually diminishing until they disappear at or about a point c', where they merge into the cylindrical surface of the ram. This point c' is situated about midway of the length of the recoil movement. With this apparatus when the recoil 90 takes place the pressure in the space a of the cylinder A due to the movement of the piston in the direction of the arrow in Fig. 1 forces the liquid from said space a through the passages b and against the forward end of the 95

100

sleeve-valve b^3 , thereby causing the latter to slide away from its seat b^4 against the resistance of the spring b^4 and leaving a clear passage for the liquid to flow into the interior of the hollow piston-rod. On completion of the recoil movement the spring b^4 reacts and pushes the sleeve-valve b^3 forward against its seat b^4 , thereby shutting off the return or escape of the liquid from the hollow piston-rod through the passages b when the gun is run forward to its firing position. During the running forward of the gun and the return movement of the piston and piston-rod the liquid within the hollow piston-rod and around the ram exerts pressure on the rear end of the sleeve-valve and, in conjunction with said spring b^4 , keeps it pressed hard up against its seat b^4 . Therefore the only escape for the liquid from the interior of the piston-rod is by way of the taper groove or grooves formed by the flat or flats c on the ram and by way of the small uniform groove or passage b^2 in the bushing b' , these taper grooves or flats c and the passages b^2 being so arranged that the widest or deepest part of the taper grooves or flats lies opposite the uniform grooves or passages when the piston-rod is in its recoiled position. As the said flat or flats c on the ram extend only about half of the length of recoil movement, as aforesaid, the escape of the liquid is during the return of the gun gradually diminished until toward the completion of the forward movement of the gun the only escape for the liquid is through the small uniform passage b^2 in the bush b' . Consequently the gun is brought very quietly to rest in its firing position.

In the modified arrangement illustrated by Figs. 4, 5, and 6 we have dispensed with the aforesaid sleeve-valve and have provided a non-return valve b^5 at the inner or rear end c^2 of the ram C . This end c^2 is furnished with a cap c^3 , whose outer diameter fits the interior of the hollow piston-rod B and is formed with a uniform groove or passage c^4 . The end c^2 of the ram is also formed with a central hole c^5 , which extends forwardly and diverges at c^6 to the circumference at a point in advance of the forward end of said cap c^3 . At the mouth of the said hole c^5 , within a space c^7 , provided for its reception in the cap c^3 , is located the non-return valve b^5 . The end of the said cap c^3 is perforated at c^8 to permit of liquid reaching the said space c^7 from the interior of the hollow piston-rod. Along the interior surface of the hollow piston-rod are formed one or more longitudinal taper grooves b^6 , said grooves opening at their ends of greatest area into the passage or passages b , through which communication is established between the space a of the recoil-cylinder and the interior of the hollow piston-rod. The said taper grooves extend rearwardly and gradually diminish in area until they merge into the cylindrical inner surface of the piston-rod at

about the point b^7 . During recoil the pressure in the space a of the cylinder A forces the liquid through the passages b in the piston-rod B into the annular space around the ram C , thence through the holes c^6 c^5 in said ram, past the valve b^5 , and through the perforations c^8 in the cap c^3 , whereby said liquid reaches the space within the hollow piston-rod and keeps it filled with liquid as the said rod is withdrawn from the ram C . On the completion of the recoil and in the return movement of the gun the aforesaid valve b^5 under the pressure of the liquid within the hollow piston closes the passage c^5 . Consequently the only way of escape left for the liquid from said hollow piston-rod is by the small uniform groove c^4 in the cap c^3 and the taper grooves b^6 in the piston-rod leading to the passages b . As these grooves b^6 gradually diminish in area, it follows, as in the previous example, that during the return movement of the piston and its rod the gun will be very gradually brought to rest as it terminates its forward movement.

What we claim, and desire to secure by Letters Patent of the United States, is—

1. In recoil apparatus for guns, the combination with the hollow piston-rod and the ram, of a valve adapted to open during the recoil movement of the piston to admit the pressure liquid from the recoil-cylinder into the hollow piston-rod and adapted to close on the commencement of the return or forward movement of the said piston, and of means whereby the liquid in the hollow piston-rod can only escape back to the recoil-cylinder through an opening or passage which gradually diminishes in area during the said forward movement of the piston, for the purpose specified.

2. In recoil apparatus for guns, the combination with the ram and the hollow piston-rod having passages therein capable of communicating with the interior and exterior of said hollow piston-rod, of means for opening said passages during the recoil movement of the gun and for closing them during the return movement of the gun, and of a taper passage between said ram and piston-rod for controlling the said return movement of the gun, substantially as described.

3. In recoil apparatus for guns, the combination with the ram and the hollow piston-rod having passages therein capable of communicating with the interior and exterior of said hollow piston-rod, of a valve for opening said passages during the recoil movement of the gun and for closing them during the return movement of the gun, and of a taper passage between said ram and piston-rod, for controlling the return movement of the gun, substantially as described.

4. In recoil apparatus for guns, the combination with the ram and the hollow piston-rod having passages therein capable of communicating with the interior and exterior of the said hollow piston-rod, of a spring-controlled

valve on the piston, of a bushing within the piston serving as a seat for said valve adjacent to the said passages in the piston-rod, of flattened taper longitudinal portions on said 5 ram and of uniform longitudinally-grooved portions on said piston-rod, substantially as and for the purpose specified.

In testimony whereof we have hereunto set

our hands, in presence of two subscribing witnesses, this 29th day of November, 1901.

ARTHUR TREVOR DAWSON.
GEORGE THOMAS BUCKHAM.
